(57) **CLAIM**

The ornamental design for a support for fiducial markers, as shown and described.

DESCRIPTION

FIG. 1 is a perspective view of one embodiment of a support for fiducial markers showing our new design incorporated into a longitudinal axis tool;

FIG. 2 is an enlarged top plan view thereof;

FIG. 3 is a right side elevational view thereof;

FIG. 4 is a front elevational view thereof;

FIG. 5 is a left side elevational view thereof;

FIG. 6 is a rear elevational view thereof;

FIG. 7 is a bottom plan view thereof;

FIG. 8 is a perspective view of another embodiment of a support for fiducial markers showing our new design incorporated into a longitudinal axis tool;

FIG. 9 is an enlarged top plan view thereof;

FIG. 10 is a right side elevational view thereof;

FIG. 11 is a front elevational view thereof;

FIG. 12 is a left side elevational view thereof;

FIG. 13 is a rear elevational view thereof, and,

FIG. 14 is an enlarged bottom plan view thereof.

The broken lines shown in the figures are included for the purpose of illustrating portions of the support for fiducial markers and form no part of the claimed design.
